Primary Examiner — Katie Jane Stofko(74) Attorney, Agent, or Firm — Weintraub Tobin; Eric Caligiuri(57) CLAIM

The ornamental design for a heart shaped flower lollipop, as shown and described.

DESCRIPTION

FIG. 1 is a front, top and right side perspective view of a heart shaped flower lollipop according to the present invention;

FIG. 2 is an enlarged view thereof, taken from FIG. 1;

FIG. 3 is a front elevation view thereof;

FIG. 4 is a right side elevation view thereof;

FIG. 5 is a top plan view thereof; and,

FIG. 6 is a bottom plan view thereof.

The dashed broken lines encircling the enlarged view are for annotative purposes only and form no part of the claimed design.

1 Claim, 5 Drawing Sheets(56)
